CLIFFORD HUGH DOUGLAS, OF PATCHAM, ENGLAND.

SUPPLY OF ENERGY TO ELECTRIC-RAILWAY SYSTEMS.

1,163,514.

Specification of Letters Patent.

Patented Dec. 7, 1915.

Application filed June 25, 1915. Serial No. 36,389.

To all whom it may concern:

Be it known that I, CLIFFORD HUGH DOUGLAS, a subject of the King of Great Britain, and a resident of Patcham, England, have invented a new and useful Improvement in the Supply of Energy to Electric-Railway Systems, of which the following is a specification.

This invention relates to electric railway systems of the kind in which direct current is supplied to an insulated conductor from which it is collected in a known manner by a shoe or collector bow and transmitted to direct current motors on the trains. The running rails are bonded and used for the return current.

Since the system of energy supply of this invention hereinafter described renders the location of the circuit interrupting devices in the motor circuits equally effective whether placed on or off the moving trains the system is equally applicable to trains with or without drivers. In the latter case it may be desirable to employ separately excited or compound wound motors in which case an independent conductor may convey the shunt field current, but the system as described is independent of the type of direct current motor employed.

Sections of the conductor rail or wire which may correspond in length and position to signal block sections are insulated from each other. Treadles of the usual depression, or other known type, operated by the train, are placed at or near the entrance of such rail sections and block section switches are placed in the feeder circuits to each of the sections in such a manner that when operated by a passing train the section behind that occupied is made "dead" but made "alive" again on the train passing to the section still farther ahead. It will be understood that in this way there is one and only one "dead" section immediately behind each train.

According to the present invention the pressure applied to any given section is entirely controlled at any given time by a generator, installed in the manner hereinafter indicated and connected to the said section in a manner hereinafter described by way of example. The pressure of this generator is determined by the resistance interposed in its field circuit and the amount of this interposed resistance is suitably controlled by an automatic regulating device set in motion

by the current taken by the train. The well known potentiometer connection type of field resistance may advantageously be employed. This operation may be further controlled by any difference of pressure between two sections not to be supplied from the same sub-station as hereinafter described or in addition the motion of the field rheostat comprising such resistance may be arrested by limit switches designed in a known manner to prevent the current due to the pressure from rising beyond a predetermined amount.

In the example herein described and illustrated in the accompanying drawing, the generator forms part of a motor generator set consisting of two generators and one motor which latter is not shown and may be of any convenient type. Each generator will have a suitable maximum pressure approximately equal to that required by the train motors when running at full speed. Said generator will normally be driven at a constant speed by its motor and (when not supplying current) be excited to such a degree as will suffice to produce the full accelerating current through the train motors when at rest. On the closing of the circuit between the generator and the train motors, such closing being performed by a switch either on the train or elsewhere, and assuming that the circuit is not further interrupted by the block section switches previously referred to, the train will start. By the action of a relay operated by the current supplied to the motors, the circuit to the operating mechanism of the field rheostat will be closed and the rheostat will operate, raising the pressure at a predetermined rate and accelerating the train.

In the system of my invention each train is started and driven over a distance limited only by the economic radius of energy distribution at the pressure employed, by current produced by one generator which at any one time is only supplying current to a single train. No resistance need be inserted or cut out from the main motor circuit when the speed is to be altered; the conductor rails are kept at the potential required under the existing conditions irrespective of the load on the train or the number of units constituting the train and the waste of energy in the controlling resistances is greatly lessened and the connections simplified.

In order that two or more trains may be

running on the track in the same direction at the same time between each distributing center two or more generators are installed and the arrangement is such in the example 5 described (which shows two generators) that, when a treadle switch is operated at the entrance to an insulated section by a passing train, in addition to making the section just left, dead, and the penultimate section alive again, it also throws over a 10 two-way switch so that when the section just left is made alive again said section is connected to a generator other than that which was associated with the said passing train. 15 If two or more trains are to run at the same time between two distributing stations, the multiway switches must provide for the connection, to the section behind any given train, of each generator of the number required, in rotation.

The system of supplying energy to the moving trains of this invention differs essentially from that of the well known "contact stud" or similar systems. In the latter all the "studs" or insulated sections from 20 which the moving train obtains its propulsion current are normally "dead" and such studs or insulated sections are energized and enable the moving train to receive current therefrom by its passage over and contact with them. In the present invention all the insulated sections of the conductor rail or trolley wire except that section immediately behind a train are at all times energized, that is to say are in direct connection 25 with a generator or generators and therefore the usual pick up coils or devices provided for energizing the conducting studs or sections hitherto employed are dispensed with.

It is to be noticed that according to this invention (a) the conductor rail is by the connections employed as regards one area of distribution, that is to say the sections 30 energized from one sub-station, electrically continuous in front of a train up to the point where it is blocked by a preceding train (b) none of the switches employed are required to operate when current is flowing through them (c) any failure of a treadle merely 35 blocks the train behind it.

In order that the nature of the invention 40 may be clearly ascertained, it will now be described with reference to the accompanying drawing which shows diagrammatically by way of example, but not of limitation, one arrangement of the circuits and the various switches together with the means whereby the same are operated at the appropriate times.

Referring to the drawing, S^1 S^2 S^3 S^4 S^5 are the clock sections of the insulated conductor of which the first three are supplied from sub-station A and the two latter from 45 sub-station B. The running rails, bonded

together, which form the return circuit, are indicated at N.

The train motors and their circuits are shown in the drawing at M and form a moving connection between N and S^1 S^2 , etc.

The circuits conveying current from the several generators to the motors on the train are shown in heavy lines while the circuits for operating the various switches, rheostats, and so forth are shown in thin lines.

Two generators a and b are shown at sub-station A and two generators c and d at sub-station B. The generators at each sub-station are arranged to be driven at a substantially constant speed by a motor (not shown). The actuating coils operating the various switches, relays, and the automatic rheostats are energized from a battery x one pole of which is connected to the earth-return N and the other pole is connected to a battery wire 10. Automatically operated rheostats R^1 R^2 R^3 R^4 are included in the circuits of the field magnet windings a^1 b^1 c^1 d^1 respectively of the generators a , b , c , d . In the position shown in the drawing all 50 the resistance of each of the rheostats R^1 R^2 R^3 R^4 is in circuit with its respective field winding a^1 b^1 c^1 or d^1 . The rheostats R^1 R^2 , R^3 , R^4 are adapted to be operated automatically by means of polarized relays, solenoids, or by any suitable means in the manner hereinafter pointed out in conjunction with a dash pot y or equivalent device whereby the rate at which the rheostat cuts out resistance can be adjusted as desired.

One pole of each of the generators a , b , c , d is respectively connected to one of the bus bars B^2 B^1 B^4 B^3 the other poles of the generators being earthed as shown. Feeder circuits F^1 F^2 F^3 leading respectively from the 65 insulated sections S^1 S^2 S^3 are adapted to be connected with one or other of the bus bars B^1 or B^2 by means of the two-way switches LS^1 LS^2 LS^3 and similar feeders F^4 F^5 respectively connect the insulated sections S^4 S^5 to one or other of the bus bars B^3 or B^4 through two-way switches LS^4 LS^5 .

Solenoid operated block section switches MS^1 MS^2 MS^3 MS^4 and MS^5 are provided for opening and closing the feeder circuits 70 F^1 F^2 F^3 F^4 F^5 respectively. Two-way switches TS^1 and TS^2 respectively mechanically linked with the switches LS^1 and LS^4 are included in the circuits of the solenoids CB^1 CB^2 CB^3 CB^4 which operate the rheostats R^1 R^2 R^3 R^4 for a purpose hereinafter 75 described. Further coils ar^1 ar^2 ar^3 ar^4 are provided for operating the plungers of the rheostats R^1 R^2 R^3 R^4 respectively the circuits of which are closed by switches p^1 p^2 p^3 p^4 by solenoids respectively co-operating therewith and traversed by current from the earthed poles of the generators a b c d .

Any one of the generators a b c d driven at a constant speed and with the whole of 80

the resistance of the rheostats R^1 R^2 R^3 R^4 in their respective field windings will deliver a pressure to the insulated sections S^1 S^2 , etc., only sufficient to produce the necessary accelerating current through the train motors when at rest.

The system shown in the drawing is in the condition in which it was left by a train which has passed over the whole of the sections S^1 S^2 , etc., and was propelled by generator a as far as section S^3 and by generator d over sections S^4 and S^5 and is at present on the next succeeding section beyond section 5 (not shown). The succeeding train m now under consideration is on section S^1 and assumed to be traveling from left to right of the diagram, and with the various switches in the positions indicated in the diagram the train m will receive current from the generator b through the bus bar B^1 , thence through the switches LS^1 and MS^1 and the insulated section S^1 , the switch K being closed. Current will also flow from the other terminal of the generator b through the coil rs^2 to earth, which will close the switch p^2 . The closure of this switch completes a circuit from the battery wire 10 through the coil ar^2 of the automatic rheostat R^2 to earth. This will cause the automatic rheostat R^2 to gradually cut resistance out of the field circuit b^1 of the generator b causing this generator to deliver an increasing pressure and bringing about a corresponding acceleration of the train 35 motors m .

On entering section S^2 treadle T^1 will be depressed by the train in the known way thereby establishing a circuit from earth through coil 2 of switch MS^1 , battery wire 10 and the battery to earth. This will cause switch MS^1 to be thrown to the open position, thus cutting off the supply of current to the insulated section S^1 from the generator b which operation thus renders section S^1 45 "dead". Current will also flow from earth at treadle T^1 , coil 2 of switch LS^1 battery wire 10 and battery x to earth at N which will throw the switch LS^1 to the right. This will connect generator a through the bus bar B^2 with the feeder F^1 so that when the switch MS^1 is again closed the next train entering section S^1 will be operated by generator a . When the train reaches the entrance to insulated section S^3 , the treadle T^2 will be depressed and a circuit through coil 2 of the switch MS^2 is made in a similar manner to that already described when the treadle T^1 was depressed. In addition a circuit will also be made from earth 50 through treadle T^2 and coil 1 of switch MS^1 , battery wire 10 and battery x to earth. The coil will thereby be energized and the switch MS^1 again closed, thus energizing the block section S^1 from generator a as 55 above described, section S^2 being at the same

time rendered "dead" by the opening of the switch MS^2 . The depression of treadle T^2 also completes a circuit through coil 1 of switch PS thereby insuring closure of this switch. Closure of switch PS completes a 70 circuit from the energized section S^3 through the switch TS^2 and coil CB^3 or CB^4 of one or other of the automatic rheostats R^3 R^4 depending on the position of the linked switches TS^2 and LS^4 , which determine 75 whether the generator c or the generator d will supply current to the train, and thence to the feeder F^4 , generator c or d to the ground. In the position of the switches shown in the diagram the generator c will be 80 connected to the insulated section S^4 through the bus bar B^4 , switches LS^4 and MS^4 . The automatic rheostat R^3 will be operated by the solenoid CB^3 to cut out resistance from the field circuit a^1 of the generator c which 85 will consequently attain the same potential as that of the insulated section S^3 so that sections S^3 and S^4 will be at the same potential.

The coils CB^3 and CB^4 and the associated 90 plungers operating the rheostats R^3 R^4 are merely diagrammatic. In practice the means for operating the rheostats are such that the direction of motion of the rheostats is dependent upon the direction of flow of 95 the current through said coils. In this way a current flowing through coil CB^3 of rheostat R^3 from section S^3 to section S^4 , or through coil CB^4 of rheostat R^4 , according to the position of the switch TS^2 , from section 100 S^3 to section S^4 will cause the rheostats to operate so as to cut resistance out of the fields of their respective generators. Conversely if the current through either of these coils flows from section S^3 to section 105 S^4 the automatic rheostat R^3 or R^4 will be operated in the reverse direction and resistance will be cut into the fields of the generator c or d . In this way the potential of the sections S^3 , S^4 and S^5 may be made approximately equal although supplied from separate sub-stations. Similarly the coils or polarized relays CB^1 and CB^2 operate the rheostats R^1 and R^2 in a similar way so that current flowing through these coils in one 110 direction from adjacent insulated sections will cause the rheostats to operate to cut resistance out of the fields a^1 b^1 of the respective generators a b while current flowing through coils CB^1 and CB^2 in the opposite 115 direction will cause the rheostats R^1 and R^2 to cut resistance into said field windings.

As the train proceeds from section S^3 to section S^4 the treadle T^3 is depressed and connections are thereby made from earth 120 through coil 2 of switch MS^3 opening said switch and through coil 2 of switch PS thereby opening the same and through coil 2 of switch LS^3 thereby throwing over switch LS^3 and connecting generator a 130

through bus bar B² with switch MS³ so that when this switch is next closed the following train to that, the procession of which is now being described, will receive energy while on sections S¹ S² or S³ from generator a and not from generator b which furnished energy to the train under consideration. The opening of switch PS deprives coil CB³ of rheostat R³ of current, but the pressure 10 of the generator c will be maintained owing to the closing of switch p³ by the current to the train. As the feeder F³ is opened by the opening of switch MS³ generator b will no longer deliver current, and consequently 15 switch p² will be opened and the pressure of generator b will fall to its initial pressure owing to the rheostat R² returning to the position in which all of its resistance is again cut into the field b¹ due to circuit of 20 the coil ar² having been opened by switch p². The train having entered section S⁴ and the switch LS⁴ being in the position shown, current will, as stated above, be delivered to the train on this section from 25 the generator c, bus bar B⁴, switch LS⁴ and feeder F⁴. As shown, section S⁵ is blocked by a preceding train and the further procession of the train under consideration when this block is released by the preceding 30 train is similar to that already described. To operate trains on a single line in either direction additional treadles must be provided at the entrance to each section considered with respect to the direction of motion 35 of the train. The treadles and arrangements for depressing the same must be such that only those treadles appropriate to the direction of movement of the train will be operated. In the case of a double line the 40 arrangements herein described will be duplicated.

The trains shown in the accompanying drawing and hereinabove described are adapted to be operated by a motorman located on the train by the manipulation of the switch K. If the trains are to be propelled without drivers manually operated switches actuated by a switchman or train despatcher will be included in the feeders at the stations.

While I have described two generating sub-stations A and B each provided with two generators, I wish it understood that only a single sub-station may be used or a greater number than two, and more than 55 two generators in each sub-station if necessary, depending upon the length of line and other conditions well understood by electrical engineers.

As hereinabove described the provision of two generators at each sub-station, and the provision of two-way switches between the bus bars to which they are connected and the feeders of the insulated section enable 65 two trains to be operated automatically

each by its own generator at the same time in the area of distribution served by a sub-station. In order that more than two trains may be running at the same time in the same direction within the area of distribution served by a single sub-station, generators and switches with as many different positions as there are trains to be simultaneously driven must be provided for connecting the feeders in turn with the respective bus bars of each of the generators of which one must be provided to supply energy to each train.

I claim as my invention:

1. In an electrically operated railway system the combination with a supply conductor divided into insulated sections and a generator for each section for supplying electric energy thereto, of means set in motion by the current taken by a train in one section for varying the potential of the generator feeding the succeeding section. 80
2. In an electrically operated railway system the combination with a conductor rail divided into insulated sections and a generator for each section for supplying electric energy thereto, of means set in motion by the current taken by a train in one section for varying the resistance in the field circuit of the generator for supplying energy to the 90 succeeding section. 95
3. In an electrically operated railway system the combination with a contact conductor divided into insulated sections and a generator for each section for supplying electric energy thereto, of rheostats one for 100 varying the amount of resistance in the field circuit of each generator and means for automatically operating the rheostat of one field circuit when the train is in a preceding 105 section, said means being controlled by the current taken by the train. 110
4. In an electrically operated railway system the combination with a supply conductor divided into insulated sections, of a plurality of generators for supplying energy thereto and switching devices controlled by the passage of the train for connecting one of said generators at a time to the insulated sections of the supply conductor in succession and for disconnecting each of said sections from said generator after the train has passed to a succeeding section. 115
5. In an electrically operated railway system the combination with a conductor rail divided into insulated sections and a plurality of generators for supplying energy thereto, of switching devices the actuation 120 of which is controlled by the movement of the trains for selectively connecting said generators to successive insulated sections of the conductor rail and for disconnecting said sections from said generators after the 125 passage of a train thereover. 130

6. In an electrically operated railway system the combination of a supply conductor divided into insulated sections, a plurality of generators for supplying energy thereto, 5 automatically operated switches controlled by the passage of the train for connecting and disconnecting said generators from the insulated conductor sections and automatically operated switches also controlled by 10 the passage of the train for selecting one of said generators to supply energy to each train during its passage over the whole of said insulated conductor sections.
7. In an electrically operated railway system 15 the combination of a supply conductor divided into insulated sections, a plurality of direct-current generators for supplying energy thereto, means controlled by the current taken by the trains for varying the potential of each of said generators, automatically operated switches controlled by the passage of the train for connecting and disconnecting said generators from the insulated conductor sections and automatically 20 operated switches also controlled by the passage of the train for selecting one of said generators to supply energy to each train during its passage over the whole of said insulated conductor sections.
8. In an electrically operated railway system 25 the combination with a supply conductor divided into insulated sections, a plurality of generators for supplying energy

to said sections, power operated switches controlled by the passage of the train for governing the connection and disconnection of said generators to said sections and power operated switches also controlled by the passage of the train for selecting one of said generators other than that furnishing energy to the train the passage of which has controlled the operation of said switches to supply energy to the sections for the next succeeding train passing thereover.

9. In an electrically operated railway system 30 the combination with a supply conductor divided into insulated sections, a plurality of substations each having a plurality of generators for supplying energy to said sections, means controlled by the current taken by the train for varying the potential of each of the generators in said substations and means controlled by the passage of the train for causing the potential of a generator in an adjacent substation to adjust itself 35 automatically to that of the generator in the preceding substation supplying energy to the train.

In testimony whereof, I have hereunto subscribed my name this fourteenth day of 40 June 1915.

CLIFFORD HUGH DOUGLAS.
